UNITED STATES PATENT OFFICE.

ALBERT J. JOHNSON, OF DETROIT, MICHIGAN, ASSIGNOR OF ONE-HALF TO AUGUST J. MALEK, OF DETROIT, MICHIGAN.

DESIGN FOR A GAS-BURNER.

54,848.

Specification for Design.

Patented Apr. 13, 1920.

Application filed October 17, 1919. Serial No. 331,486. Term of patent 7 years.

To all whom it may concern:

Be it known that I, ALBERT J. JOHNSON, a citizen of the United States of America, residing at Detroit, county of Wayne, and State of Michigan, have invented a new, original, and ornamental Design for a Gas-Burner, of which the following is a specification, reference being had to the accompanying drawing, forming a part thereof.

Figure 1 is a top plan view of my gas burner.

Fig. 2 is an elevational view.

Fig. 3 is an elevation taken at right angles to the view in Fig. 2.

In the drawings; *a* is the encircling side wall, *b* is the gas inlet opening, *c* indicates the perforations through which the gas is projected to be lighted and *d* is a central draft opening through the bottom of the burner. This burner is designed for attachment to the gas supply pipe of a gas stove or hot plate and is shaped to blend harmoniously with the outline of conventional manufacture.

I claim:

The design for a gas burner, as shown in the drawings.

ALBERT J. JOHNSON.
